INTERNAL COMBUSTION ENGINE

John L. McGonigall, Philadelphia, Pa.

Substitute for application Serial No. 11,511,
March 16, 1935. This application January 18,
1938, Serial No. 185,554

2 Claims. (Cl. 123—63)

The present invention relates to the art of internal combustion engines, and particularly to a type wherein the usual form of piston, piston and connection rods so classified, are eliminated, 5 and in their stead a core is operable between stationary parts of the engine cylinder, for example between an interior stationary part and an exterior stationary part, the firing strokes for operating the core taking place at alternate 10 periods, and which construction and operation constitute the essential features of this type of engine.

This application is a substitute for application Serial No. 11,511, filed March 16, 1935, the latter 15 application being a substitute for application Serial No. 571,208, filed October 26, 1931.

Another purpose is to provide an improved mechanism operatively connecting with the crank shaft of the engine for actuating intake and exhaust poppet valves, which permit of the intake 20 of the fuel and the exhaust of the utilized gases.

Still another purpose is to provide, in an internal combustion engine of this type, an improved means of construction such as will afford a water jacket for the exterior and interior elements of 25 the engine casing.

Another purpose is to provide in a Diesel type of engine a core movable between interior and exterior parts of the engine cylinder, with means 30 for admitting a mechanism, actuated by connections with the crank shaft for the admission of oil in its crude state, and adapted to be fired, as a result of compression action at opposite ends of the core.

It is to be understood that the particulars herein given are in no way limitative, and that while still keeping within the scope of the invention, any desired modification of details and proportions may be made in the construction of the 40 appliance according to circumstances.

The invention comprises further features and combination of parts to be hereinafter set forth, shown in the drawings and claimed.

In the drawings:

Figure 1 is a vertical sectional view through the improved internal combustion engine constructed in accordance with the invention to illustrate the type adapting gasoline as its fuel.

Figure 2 is a sectional view on line 2—2 of Figure 1, showing a multiple of cylinders, wherein the core of one cylinder is in a position remote from a similar core in the other cylinder.

Figure 3 is a transverse sectional view on line 3—3 of Figure 1.

Figure 4 is a detail perspective view of the piston.

Figure 5 is a vertical sectional view through a type of engine similar to that in Figures 1 and 2, insofar as the reciprocating piston is concerned, 60 and wherein oil is used as fuel, the firing of the

same occurring as a result of its being compressed.

Figure 6 is a sectional view on line 6—6 of Figure 5 showing a multiple of cylinders and also illustrating a scavenger pump or compressor, employed for blowing the utilized gases from the cylinder.

Figure 7 is a transverse sectional view on line 7—7 of Figure 5.

Referring to the drawings, 1 identifies a supporting frame for the exterior wall 2 of the engine cylinder 3, the exterior 2 being made rigid with the interior stationary core element 4 of the cylinder, by means of a cylinder head 5. The exterior wall of the engine cylinder has a water jacket 6, which communicates with a jacket 7 in a portion of the cylinder head 5, which jacket in turn communicates with the water jacket 8 of the stationary core of the engine cylinder. Operative between the exterior and interior stationary 10 elements of the engine cylinder is a movable piston 9 provided with downwardly depending arms 10, which are connected by a pin 11 to a pitman 12, which in turn is pivotally connected at 13 to the crank arms 14 of the crank shaft 15, which may be mounted in bearings of a foundation. 25

The interior stationary element of the engine cylinder is provided with the usual packing rings 16, while the contracted end 17 of the movable core is provided with similar packing rings 18.

The cylinder head 5 is formed with intake and exhaust passages 19 and 20, to which the intake and exhaust pipes 21 and 22 are connected as shown. The intake and exhaust passages 19 and 20 communicate with intake and exhaust passages 23 and 24 formed interiorly of the interior stationary core element of the engine cylinder. Also operatively mounted in the passages 23 and 24 are poppet valves 25 and 26, which have rods 27 and 28 extending down through the passages 23 and 24, and through the packing glands 29 and 30.

The upper ends of the intake and exhaust pipes 21 and 22 communicate, by means of the passages 31 and 32 with the combustion chamber 33 of the outer casing of the engine cylinder, so as to permit of the intake of the fuel at 31 and the exhaust of utilized gases at 32. At points where the pipes 21 and 22 communicate with the passages 31 and 32 poppet valves 34 and 35 control the valve openings 36 and 37. The poppet valves 34 and 35 are connected to operating rods 38 and 39, which are spring tensioned at 40 for normally closing the valves 34 and 35. The rods 38 and 39 are more or less guided in recesses 41, where the cylinder head 5 registers with the flanged end of the outer casing of the engine cylinder. Below where the valve rods 38 and 39 are guided at 41, their lower ends are connected by means of plates 42 to rods 43 and 44 which are 55 60 65 70 75 80 85 90 95 100 105 110 115 120 125 130 135 140 guided in bearing arms 45, which are made integral with the frame 1 of the engine.

The valve rods 27 and 28 are also guided at 46 through the bearing arms 45 and are spring 5 tensioned at 47. The lower ends of the valve rod 27 and 28 are inclined laterally at their lower portions as shown at 48, and their lower extremities are connected by the plates 49 to cam actuated rods 50 and 51, which are guided in the bearing 10 arms 52 also constituting integral parts of the frame 1, the rods 43 and 44 which actuate the poppet valves 34 and 35 also passing through the bearing arms 52.

Journalized in bearings of the frame 1 are cam 15 shafts 53 and 54 having gears 55 and 56, which mesh with the gear 57 mounted upon the crank shaft 15, in this manner power is transmitted to the cam shafts 53 and 54 for rotating the same and thereby bringing the cams in engagement 20 with the rods 43 and 44 and 51. There are two cams 58 and 59 on the camshaft 54, and two cams 60 and 61 on the cam shaft 53. The rods 44 engage with the cams 59, while the rods 51 engage with the cams 58. That is, the lower ends of these 25 rods ride over the cams, and the lugs 62 and 63 ride under the lower extremities of the rods, imparting movement to the rods 44 and 51, for opening the exhaust poppet valves 26 and 35. The rods 43 and 50 have their lower extremities 30 riding on the surface of the cams 60 and 61, so that the cam lugs 64 and 65 will ride under the extremities of the rods 43 and 50 and impart movement thereto for opening and closing the poppet intake valves 25 and 34, the purpose of admission of fuel into the combustion chamber 33 35 and into the combustion chamber 66, at a point between the core 4 and the interior of the piston 9. The piston 9 is movable and its lower sleeve portion 67 telescopes the core 4. The core 40 4 has a passage 68 through which a lead wire 69 may connect with a conventional type of spark plug 70. A similar spark plug 71 is mounted in the cylinder head of the outer wall of the cylinder casing.

Obviously Figure 1 shows the piston 9 on the 45 verge of a firing stroke, hence on the verge of an exhaust stroke in the combustion chamber 33. Upon the piston 9 moving upward the exhaust valve 35 will open, and in which case the core 9 will force the utilized gases through the exhaust 50 pipe 22, in this instance the intake poppet valves 25 and 34 remain closed. The momentum of the core 9 is sufficient to carry it upward, and then downward and again upward. On the down 55 stroke of the piston 9 fuel is admitted by the opening of the poppet valve at 47 in the combustion chamber 33, and on the upward stroke this charge is compressed. However, on the down stroke the poppet valve 26 opens and therefore 60 permits exhaust of the utilized gases from the combustion chamber 66 by the opening of the valve 26. Immediately following the compression stroke as the piston 9 moves upward the charge in the combustion chamber 33 is fired, then the 65 piston 9 moves downward as a result of firing the charge in the combustion chamber 33, and upon so moving downward, a new charge having been drawn past the poppet valve 25 on the compression of the charge in chamber 33, is fired in the 70 combustion chamber 66. These cycles of operation are alternately repeated, resulting in the operation of the engine as disclosed in Figures 1, 2 and 3.

Referring to Figures 5, 6 and 7, which is of a 75 Diesel type of internal combustion engine, using

oil as fuel, the power being derived as a result of first compressing air in the cylinder and then the fuel is injected in the combustion chambers.

In this type of engine a frame 72 is provided, which supports the interior and exterior stationary elements 73 and 74 of the engine cylinder. The exterior wall 74 is provided with a water jacket 75, which communicates with the interior stationary cylinder element (which has a water jacket 76), by means of passages 77 formed in 10 the cylinder head 78.

In this type of engine a movable piston 79 having a depending sleeve portion 80 is provided, and depending from the sleeve portion of the piston 79 are arms 81, which are pivoted at 82 to a 15 pitman 83. The pitman 83 is in turn pivotally connected at 84 to the crank arms 85 of the crank shaft 86.

The crank shaft 86 has a gear 87 meshing with a gear 88 on a cam shaft 89, which is mounted 20 in bearings of the frame 72.

The engine as disclosed in Figures 5 and 6 includes combustion chambers 90 and 91, wherein the oil fuel is compressed and thereby creating such heat as to fire the fuel.

The cam shaft 89 is provided with oppositely disposed cams 92 and 93, and projecting from the frame 72 of the engine are bearings 94 and 95, in which rods 96 and 97 are guided. The rod 96 is connected to a rod 98 by means of an arm 30 99, and the rod 98 is in turn connected to a rocker lever 100, which in turn is pivoted at 101 to a valve rod 102, which in turn actuates a poppet valve (not shown) in a casing 103. This casing 103 terminates in an injector 104, for injecting 35 fuel such as crude oil into the combustion chamber 90.

The other rod 97 is connected to a valve rod 105 by means of an arm 106. The valve rod 105 in turn actuates the poppet valve (not shown) in casing 107, and connected to the casing 107 is a pipe 108, which engages through a passage 109 and terminates in an injector 110 at the end of the passage 109, for the purpose of injecting crude oil into the combustion chamber 91. A pipe 111 is connected to the casing 107, and connected to the pipe 111 is a pipe 112 which extends vertically and communicates with the casing 103 of the poppet valve (not shown). Crude oil of the proper consistency is supplied 40 from any suitable source (not shown) to the pipe 111, which and the pipe 112 feeds the supply to and through the poppet valves (not shown). This crude oil is lifted under pressure to the poppet valves from its source of supply through a pipe 113, as in Figure 6, by means of any suitable fuel pump as identified at 114. This pump is operated from the cam shaft 89.

The cylinder head 78 is secured to the flange of the exterior engine wall as identified at 115, 45 while the central portion of the cylinder head 78 is secured to the interior core 73 of the engine cylinder by means of a screw 116.

In order to eliminate the utilized gases subsequent to explosion in the combustion chambers 50 90 and 91, and to permit a new supply of air to enter, a scavenging pump or compressor as identified at 117 is provided. This scavenging pump or compressor is similar, in general construction, to the engine itself. In other words, it comprises 55 an exterior pump cylinder wall 118 and an interior stationary pump core 119, there being a reciprocating core 120 provided with a depending sleeve 121, which has downwardly projecting arms 122, 60 which are in turn pivoted to the pitman 123 by 70 75

means of the pin 124. The pitman 123 is in turn pivoted at 125 to a crank arm 126 carried by the crank shaft 38. In this manner reciprocating movements are imparted to the reciprocating core 129, for the purpose of supplying air under pressure from the pressure chamber 127 and 128. The interior stationary core 118 has a passage 129 provided with a check valve 130, which opens when the movable core 128 operates in the direction of the arrow A, and closes when the movable core 129 moves in the opposite direction. When the core 129 moves in the opposite direction the air in the chamber 128 is forced through the passage 131 of the core 118, and through the pipe 132 and thence through the branch pipe 133, the pressure being sufficient to carry this air through either one of the branch pipes 134 and 135 and into one of the chambers 90 and 91, due to the fact that the pipe 132 connects with the branch pipes 134 and 135 at the port 136. The branch pipes 134 and 135 communicate with the chambers 90 and 91 and also communicating with the chambers 90 and 91 at points opposite the pipes 134 and 135 are outlet pipes 137 and 138. 5

10 The passage 131 of the stationary core of the scavenging pump or compressor has a check valve 139, which opens on the downward movement of the core 129, and closes on the upward movement as indicated by the arrow A.

15 20 25 30 35 40 45 50 55 60 65 70 75 80 85 90 95 100

25 The passage 131 of the stationary core of the scavenging pump or compressor has a check valve 139, which opens on the downward movement of the core 129, and closes on the upward movement as indicated by the arrow A.

30 However, when the movable core 129 moves downward in the direction of the arrow B air is drawn through the check valve 140 (which is similar to the check valve 139), into the chamber 127. On the upward movement of the movable core 129 air drawn into the chamber 127 is forced past the check valve 141, which is also similar to the check valve 139, the air passing through the portion 131a of the pipe 131, and then into the pipe 133, the air having sufficient pressure, to carry it into one of the chambers 90 and 91, through the branch pipes 134 and 135.

35 In order to start this type of internal combustion engine, which is similar in principal to the well known Diesel engine, in that crude oil of the proper consistency is used, tubes 142 communicate with the combustion chamber 91. These tubes are designed to be connected to any suitable supply of air under pressure, which may act upon the shoulders 143 of the movable cores shown in Figure 6, the pressure of air acting upon the shoulder 143 of the engine cylinder to the left in Figure 6, and there being a supply of air in the chamber 91 of the engine cylinder to the left in Figure 6, so that supply of air is compressed, and immediately following the compression of the air in the chamber 91 of the cylinder to the left in Figure 6, an injection of crude oil fuel enters the chamber, and as a result of a high temperature of heat the explosion of the fuel takes place. At this point the supply of air through the tubes 142 is shut off. In this manner the internal combustion engine shown in Figures 5 and 6 is started. The cycles of operation are as follows.

40 45 50 55 60 65 70 75 80 85 90 95 100

45 The air under pressure from the scavenging pump or compressor first enters the chamber 90 and blows out the utilized gases, and leaves a fresh supply of air therein, and when the movable piston 79 operates upwardly, it compresses the supply of air, and then the proper amount of crude oil is injected from the injector 104 into the chamber 90, which results in an explosion. When the movable piston 79 is moving upwardly

5 and compressing the air in the chamber 90 ports 144 of the depending sleeve of the movable piston 79 register with the branch pipe 135 and the outlet pipe 138, allowing air from the scavenging pump or compressor to blow out the utilized gases in the chamber 91, thereby leaving a fresh supply of air therein. Then on a downward stroke of the movable piston 79, the air in chamber 91 compresses, and instantly following fuel is injected through the injector 104, resulting in an explosion. These steps of operation alternately repeat, and thereby impart revoluble movement to the crankshaft 38, from which power may be transmitted to any desired source.

15 The invention having been set forth, what is claimed is:

1. In an internal combustion engine, the combination with a power cylinder consisting of an exterior wall having a cooling jacket and provided with opposed pressure power chambers, of a stationary core element fixed within one of said chambers with its cylindrical periphery in spaced relation to the interior surface of said cylinder, a movable solid piston mounted for reciprocating movement in the other pressure power chamber and having a depending sleeve telescoping over the stationary core element and reciprocating in the space between the stationary core element and the cylinder wall, a crank shaft operatively connected to and being impelled by said reciprocating piston element, power fuel admission means for said chambers and being in turn operatively connected to said crank shaft, certain of said power fuel admission means being mounted in and passing through said stationary core, the construction and arrangement of said power fuel admission means being such as to alternately operate, whereby reciprocating movement may be imparted to the reciprocating piston element.

2. In an internal combustion engine the combination with a power cylinder consisting of an exterior wall having a cooling jacket and provided with opposed pressure power chambers, of a stationary core element fixed within one of said chambers with its cylindrical periphery in spaced relation to the interior surface of said cylinder, a movable solid piston mounted for reciprocating movements in the other pressure power chamber and having a depending sleeve telescoping over the stationary core element and reciprocating in the space between the stationary core element and the cylinder wall, a crank shaft operatively connected to and being impelled by said reciprocating piston element, power fuel admission means for said chambers and being in turn operatively connected to said crank shaft, certain of said power fuel admission means being mounted in and passing through said stationary core, the construction and arrangement of said power fuel admission means being such as to alternately operate, whereby reciprocating movement may be imparted to the reciprocating piston element.
